(57) **CLAIM**

The ornamental design for a hanging apparatus with movable hooks, as shown and described.

DESCRIPTION

FIG. 1 is a perspective view of a hanging apparatus with movable hooks showing a first embodiment of our new design with a hook placed in a first position.

FIG. 2 is a front elevation view of the hanging apparatus with movable hooks of FIG. 1.

FIG. 3 is a back elevation view of the hanging apparatus with movable hooks of FIG. 1.

FIG. 4 is a right elevation view of the hanging apparatus with movable hooks of FIG. 1.

FIG. 5 is a left elevation view of the hanging apparatus with movable hooks of FIG. 1.

FIG. 6 is a top plan view of the hanging apparatus with movable hooks of FIG. 1.

FIG. 7 is a bottom plan view of the hanging apparatus with movable hooks of FIG. 1.

FIG. 8 is a perspective view of a hanging apparatus with movable hooks showing the first embodiment of our new design with the hook placed in a second position.

FIG. 9 is a front elevation view of the hanging apparatus with movable hooks of FIG. 8.

FIG. 10 is a back elevation view of the hanging apparatus with movable hooks of FIG. 8.

FIG. 11 is a right elevation view of the hanging apparatus with movable hooks of FIG. 8.

FIG. 12 is a left elevation view of the hanging apparatus with movable hooks of FIG. 8.

FIG. 13 is a top plan view of the hanging apparatus with movable hooks of FIG. 8; and,

FIG. 14 is a bottom plan view of the hanging apparatus with movable hooks of FIG. 8.

The broken lines represent portions of the structure that forms no part of the claim.

1 Claim, 8 Drawing Sheets
